FLOOR WAXING DEVICE

Raymond W. Bales, Fresno, Calif.

Application August 8, 1958, Serial No. 753,964

3 Claims. (Cl. 15—98)

This invention relates to floor polishing implements, and more particularly to a device for applying floor wax.

A main object of the invention is to provide a novel and improved applicator for polishing wax, said applicator being simple in construction, being easy to use, and providing an economical and efficient distribution of floor wax of the paste type on a surface to be polished.

A further object of the invention is to provide an improved dispensing applicator for floor wax or similar polishing wax, said applicator involving inexpensive components, being durable in construction, being compact in size, and being easy to manipulate.

A still further object of the invention is to provide an improved applicator for floor polishing wax which provides a high degree of economy in the utilization of the floor wax, as well as uniform spreading of the wax on the floor surface and minimum loss of wax through evaporation from the applicator.

Further objects and advantages of the invention will become apparent from the following description and claims, and from the accompanying drawings, wherein:

Figure 1 is a perspective view of a floor polishing machine provided with an improved wax applicator according to the present invention.

Figure 2 is an enlarged perspective view of one of the head members of the machine of Figure 1 showing the flexible cover member and resilient clamping ring associated therewith, separated from the head member.

Figure 3 is a perspective view of the head member of Figure 2 with the cover and resilient clamping ring engaged thereon.

Figure 4 is an enlarged vertical cross sectional view taken on the line 4—4 of Figure 3.

Figure 5 is a vertical cross sectional view taken on the line 5—5 of Figure 4.

Figure 6 is a side elevational view, partly in vertical cross section, of a modified form of applicator head embodying the present invention.

Figure 7 is a horizontal cross sectional view taken on the line 7—7 of Figure 6.

Referring to the drawings, and more particularly, to Figures 1 to 5, 11 generally designates a floor polishing machine which comprises the conventional bottom housing 12 to which is attached the operating handle 13, the housing 12 containing an electric motor and conventional coupling means to drivingly connect the motor to a pair of rotatable head members 14 disposed beneath the housing 12, said head members being of conventional construction and being provided with the upstanding castellated shaft portions 15 adapted to be drivingly coupled to driving shaft elements, not shown, incorporated in the housing 12 and being of conventional construction.

Each of the floor-engaging head members 14 is provided on its bottom surface with a resilient deformable spreader pad 16 of any suitable cushioning material, such as sponge rubber or the like. The main body portion of the head member 14 is formed with a diametrically extending passage 17 communicating with a central bore 18

2

which merges with the central aperture 19 formed in the spreader pad 16. As shown in Figure 4, the horizontal passage 17 opens at diametrically opposite side portions of the generally circular main body of the head member 14.

Disposed in the passage 17 is the horizontally extending conduit 20 provided at one end with a closure plug 21 and at the other end with a conduit fitting 22. The horizontal conduit member 20 includes T-fitting 23 at its intermediate portion to the stem of which is connected a conduit 24 which depends through the bore 18 into the aperture 19, as is clearly shown in Figures 4 and 5.

Secured to the operating handle 13 are a pair of spaced, generally U-shaped resilient spring clips 25, 25 in which is supported a dispensing cylinder 26. The dispensing cylinder 26 is of generally conventional construction, similar to a conventional caulking gun, the cylinder being provided with a dispensing piston having an externally projecting piston rod 27 extending through a handle 28 rigidly secured to the top end of the cylinder 26 and containing the pivoted cooperating handle lever 29 which is engageable with notches 30 formed in the rod 27 so as to force the rod downwardly when squeezing force is exerted between the stationary handle 28 and the pivoted handle 29. The cylinder 26 is provided at its lower end with a discharge nozzle 30' to which is connected a flexible conduit 31 having a fitting 32 at its free end adapted to lockingly engage with the conduit fitting 22 on the end of the tubular member 20 of each head member 14. Thus, material from the cylinder 26 may be discharged into each head member by first connecting the conduit fitting 32 to the conduit fitting 22 of the head member and then manipulating the discharge lever 29 by exerting squeezing pressure between the stationary lever 28 and the discharge lever 29, as above described.

Each member 14 is formed with a peripheral groove 33 adapted to receive the marginal portion of a cover member 34 of flexible porous sheet material, such as of suitable fabric material, the marginal portion of said cover member being locked in the groove 33 by a resilient clamping ring 35, comprising a coiled spring, or any other suitable elastic material. Thus, with the cover member 34 secured on the head member 14 a dispensing receptacle is defined beneath the associated spreader pads 16, said receptacle being adapted to receive a quantity of floor wax and to distribute same over the floor surface to be polished.

In using the apparatus, each of the head members 14 is provided with a suitable quantity of paste wax from the cylinder 26 by connecting the conduit 31 thereto and discharging the paste wax from the cylinder in sequence. After each head member has been supplied with the paste wax, the conduit fitting 32 is engaged with a spring clip 36 provided on the upstanding collar member 37 associated with the housing 12 and receiving the handle 13. Thus, as shown in dotted view in Figure 1, the conduit fitting 32 may be lockingly engaged in the spring clip 36, allowing the apparatus to be thereafter used in its normal manner, whereby the paste material, shown at 40, in each of the applicator head members 14, will be distributed uniformly beneath the associated spreader pad 16, as shown in Figure 5, and will thereafter be distributed onto the floor surface as the heads 14 are rotated and moved over said floor surface. After the material has been applied and additional material is required, the head members may be replenished by connecting the conduit fitting 32 to the fittings 22 and by supplying material thereto from the cylinder 26 in the manner above described.

In the form of the invention illustrated in Figures 1 to 5, the floor waxer 11 is similar to conventional home floor waxers which employ a pair of rotary head mem-

bers. In the embodiment illustrated in Figures 6 and 7, the floor waxer is similar to the heavy-duty type employed for industrial purposes, and comprising a single circular body 14'. The body 14' is formed with a pair of diametrically opposite radial passages 17', 17' communicating with interior horizontal passages 18' formed in the body 14', as shown in Figure 6, and further formed with vertical passages 19' communicating with apertures 20' formed in the circular resilient spreader pads 21' secured to the bottom surface of the main body member 14'. Respective conduit members 22' are mounted in the passages 18', said conduit members being communicatively connected at their intermediate portions to radially extending conduits 23' disposed in the radial passages 17' and being provided at their outer ends with conduit fittings 24'. The horizontal passages 18' communicate at their opposite ends with the vertical passages 19', which merge with the apertures 20', and disposed in the horizontal passages 18' are respective horizontal conduits 22'. The horizontal conduits 22' are provided at their ends with depending conduit portions 25' which extend through the vertical passages 19' and into the apertures 20' in the spreader pad 21'.

The circular main body 14' is formed with a peripheral groove 33', and a cover member 34' of flexible porous sheet material, such as fabric, or the like, is detachably secured over the spreader pad 21' by a resilient clamping ring 35 which locks the marginal portions of the cover member 34' in the groove 33', as is clearly shown in Figure 6.

A floor wax supply cylinder 26, not shown, is provided on the associated handle, and floor wax is supplied by engaging the conduit fittings 32 of said wax dispensing cylinder 26 with the conduit fittings 24', and manipulating the cylinder to force floor wax into the receptacle portion defined beneath the respective apertures 20' in the spreader pad 21'. Thus, the paste wax is deposited in the space between the spreader pad 21' and the flexible cover 34', after which the body member 14' is rotated in the usual manner to spread the wax evenly beneath the pad 21' and to cause the wax to be applied to the floor surface over which the apparatus is moved.

In the forms of the invention previously described, the conduit fittings 22 and 24' are of a suitable type to be lockingly coupled to the supply conduit fitting 32 on the free end of the conduit 31. Thus, the conduit fittings 24' and 22 may be provided with outwardly projecting locking pins 60 which are lockingly engageable in bayonet slots provided in the cooperating conduit fitting 32 to secure the fitting 32 in communicative coupling relationship with the receiving conduit fitting 24' or 22.

While certain specific embodiments of an improved applicator for polishing wax or similar paste material have been disclosed in the foregoing description, it will be understood that various modifications within the spirit of the invention may occur to those skilled in the art. Therefore it is intended that no limitations be placed on the invention except as defined by the scope of the appended claims.

What is claimed is:

1. In an applicator for polishing wax, a main housing open at its bottom, an elongated handle member secured to said housing, a floor-engaging head member lockingly engaged in said main housing to support same on a floor to be polished and projecting from the bottom of said housing and rotatable relative to said housing, a resilient deformable spreader pad secured to the underside of said head member, said head member being formed with a horizontal passage extending from one side thereof subjacent the bottom edge of the main housing, and said

spreader pad being formed with a vertical passage at its center portion communicating with said horizontal passage and opening beneath said spreader pad, a cover member of flexible porous sheet material detachably secured to said head member and underlying said spreader pad, defining a dispensing and spreading receptacle for floor wax between said spreader pad and the cover member, a floor wax dispensing container mounted on said handle member, discharge conduit means connected to said container, and means to detachably communicatively connect said conduit means to said passage at said one side of the head member.

2. In an applicator for polishing wax, a main housing open at its bottom, an elongated handle member secured to said housing, a floor-engaging head member lockingly engaged in said main housing to support same on a floor to be polished and projecting from the bottom of said housing and rotatable relative to said housing, a resilient deformable spreader pad secured to the underside of said head member, said head member being formed with a horizontal passage extending from one side thereof subjacent the bottom edge of the main housing, and said spreader pad being formed with a vertical passage at its center portion communicative with said horizontal passage and opening beneath said spreader pad, a dispensing conduit mounted in said passage and having a conduit fitting projecting from one side of said passage, a cover member of flexible porous sheet material detachably secured to said head member and underlying said spreader pad, defining a dispensing and spreading receptacle for floor wax between said spreader pad and the cover member, a floor wax dispensing container mounted on said handle member, discharge conduit means connected to said container, and means to detachably communicatively connect said conduit means to said conduit fitting.

3. In an applicator for polishing wax, a main housing open at its bottom, an elongated handle member secured to said housing, a floor-engaging head member lockingly engaged in said main housing to support same on a floor to be polished and projecting from the bottom of said housing and rotatable relative to said housing, a resilient deformable spreader pad secured to the underside of said head member, said head member being formed with a horizontal passage extending from one side thereof subjacent the bottom edge of the main housing, and said spreader pad being formed with a vertical passage at its center portion communicating with said horizontal passage and opening beneath said spreader pad, a dispensing conduit mounted in said passage and having a conduit fitting projecting from said one side of said passage, a cover member of flexible porous sheet material engageable with the bottom portion of said head member beneath said spreader pad, said bottom portion being formed with a peripheral groove, a resilient clamping ring lockingly engaging said cover member and clamping same in said peripheral groove, defining a dispensing and spreading receptacle for floor wax between said spreader pad and the cover member, a floor wax dispensing container mounted on said handle member, discharge conduit means connected to said container, and means to detachably communicatively connect said conduit means to said conduit fitting.
